UNITED STATES PATENT OFFICE.

HERMAN W. RITTER, OF BROOKLYN, NEW YORK, ASSIGNOR TO THE GOODYEAR'S METALLIC RUBBER SHOE COMPANY, A CORPORATION OF CONNECTICUT.

COVERING FOR IRREGULAR SURFACES.

1,211,624.

Specification of Letters Patent.

Patented Jan. 9, 1917.

Application filed March 4, 1915. Serial No. 12,012.

To all whom it may concern:

Be it known that I, HERMAN W. RITTER, a citizen of the United States, residing in the borough of Brooklyn, county of Kings, 5 and State of New York, have invented certain new and useful Improvements in Coverings for Irregular Surfaces, of which the following is a full, clear, and exact description.

10 The invention relates particularly to handles for articles of hand baggage and other articles having irregular surfaces and has for an object to produce a covering which is as strong and durable as those now 15 in common use and which can be produced at a much lower cost.

As an example the ordinary handle for baggage consists of a metallic or other relatively rigid form with a leather covering cemented or otherwise attached thereto. My 20 invention consists in the substitution for such leather covering, of a composite material the equal thereof in wearing qualities and appearance and which may be manufactured at a much lower cost. This saving in 25 cost of manufacture is due partially to the use of cheaper materials, and partially to the fact that waste is almost entirely eliminated and that the material is applied with 30 much less manipulation than is the case with leather, all of which is clearly set forth in the following specification and claims and illustrated in the accompanying drawing forming a part thereof, wherein:

35 Figure 1 is a perspective view of a handle; and Fig. 2 is a cross-sectional view of the same.

In the manufacture of my improved 40 covering as applied to a handle I use as a base therefor two elements *a* and *b* of metal or other relatively rigid material shaped to fit one within the other. These two elements are those ordinarily used in the construction 45 of the usual leather covered handle. These elements I cover respectively with plies *c* and *d* of stockinette or other easily conformable fabric. It is necessary in order to have 50 this covering fit snugly, to use a yieldable, elastic fabric, inasmuch as the metal elements are of irregular warped contour, and stockinette or a similar knitted fabric provides such a covering which can be stretched or compressed at will without puckering, 55 thus forming a reticulated or porous base to which rubber can be firmly attached. The

piece *c* which is applied to the element *a* need extend only slightly beyond the edge thereof and may, or may not be folded thereover. The piece *d* on the element *b*, however, is folded a considerable distance 60 over so as to completely cover the edge, as at *g*, and leave no exposed metal. These two pieces *c* and *d* are attached to the metal by glue or any other suitable cement. To the fabric covered elements I next apply coatings or layers of rubber compound *e* and *f*, respectively, which may, if desired, be colored and grained to imitate leather. As 65 with the stockinette covering, this rubber layer is easily applied smoothly, without 70 puckers or wrinkles, the composition being in an unvulcanized condition, and therefore plastic and conformable to any desired shape. The covering thus exhibits a distinct superiority over leather, which must be 75 stretched over the convex surfaces of the form, and compressed at those points that are concave. Any superfluous material may be thrown back in the batch of stock to be 80 again worked up, thereby eliminating any 85 loss from waste. The built up parts *A* and *B* are then combined as in the ordinary leather covered handle, the rings *h* and *i* inserted at the ends thereof, and the edges of the part *b* bent inwardly to firmly grip the 90 part *a*, the whole being permanently united by means of rivets *j*. The structure as now built up is next placed in the vulcanizer where the rubber is cured, the vulcanizing process firmly uniting it to the fabric base 95 and giving the whole a permanent set.

Having described my invention, what I claim and desire to have protected by Letters Patent is:

1. A rubber covered article comprising 95 a relatively rigid form, a covering of yieldable fabric attached to said form, and a layer of vulcanized rubber compound superimposed on and united to said fabric.
2. A rubber covered article comprising a 100 relatively rigid form, said form consisting of an inner element held in position and partially inclosed by an outer element, a covering of yieldable fabric attached to said form, and a layer of vulcanized rubber compound 105 superimposed on and united to said fabric.
3. A rubber covered article comprising an upper element, the edges of said upper element being bent downwardly; a lower ele- 110

ment, the edge portions of said lower element being bent upwardly to overlap and grip the edges of said upper element; and layers of yieldable fabric and vulcanized rubber compound successively applied to and united with the outer surfaces of said rigid elements.

4. A rubber covered article comprising two overlapping metallic segments, coverings of knitted fabric on the outer surfaces of said segments, vulcanized rubber superposed thereon, said fabric and rubber being turned smoothly around the edges of said outer segment and clamped between the overlapping margins of said segments.

5. A rubber covered article comprising a relatively rigid form having an irregular surface, a covering of yieldable fabric conforming smoothly to the contour of said form, and a layer of vulcanized rubber compound superimposed on and united to said fabric.

6. A rubber covered article comprising a

metallic form having a plurality of interfitting members providing an irregular surface, a covering of yieldable fabric conforming smoothly to the contour of said form, and a layer of vulcanized rubber compound superimposed on and united to said fabric.

7. A rubber handle comprising a metallic handle-like form, a layer of yieldable fabric conforming to the contour of said form, and a layer of vulcanized rubber compound superimposed on and united to said fabric.

8. A rubber handle comprising a metallic handle-like form, a layer of porous yieldable fabric adhesively secured to said form providing a smooth covering, and a layer of vulcanized rubber compound superimposed on and united to said fabric.

Signed at Naugatuck, Conn., this 2nd day of March, 1915.

HERMAN W. RITTER.
